his attorney.

UNITED STATES PATENT OFFICE.

WILLIAM COOPER, OF DENVER, COLORADO.

AMMUNITION.

1,103,740.

Specification of Letters Patent. Patented July 14, 1914.

Application filed January 15, 1914. Serial No. 312,223.

To all whom it may concern:

Be it known that I, WILLIAM COOPER, a citizen of the United States, and residing in the city of Denver, in the county of Denver and State of Colorado, have invented or discovered new and useful Improvements in Ammunition, of which the following is a specification.

My invention consists in new and useful improvements in projectiles and assembled ammunition for military, naval, sporting and general long range shooting.

Where a solid projectile, such as one of spherical, cylindrical with either flattened, truncated or conical head, or of any other exterior contour, is propelled at high speed from a gun barrel through either air or water, it meets with great resistance due to the medium which it must displace continuously as it advances and the consequent friction. This displacement of the air or water results in the formation in the rear of the flying projectile of a partial vacuum in air and of a tunnel in water of many times the diameter of the projectile itself, which vacuum or tunnel exerts a suction and further retards the projectile. The result is a slowing up of the speed of travel and a loss in flatness of the trajectory. Also, such a projectile in passing from the air into water, unless the angle of its travel to the surface closely approaches a right angle, will be deflected and frequently ricochet along the surface of the water. These objectionable features are entirely overcome by my improved projectile.

My improved projectile is of hollow cylindrical character, preferably having its bore beveled outwardly at its forward end so as to easily cleave the medium through which it is passing and to readily cut into and through the substance or material at which it is aimed. The remainder of the bore is preferably of constant diameter. The result is that there is no appreciable displacement of the medium through which the projectile passes and no area of partial vacuum or tunnel is formed in the rear of the projectile. Thus the speed of the projectile is not retarded and its trajectory is flat and true. A projectile of my improved type when passing through the air and encountering the surface of a body of water, even at a very acute angle, will enter the water readily without being turned from its line of travel and will not ricochet. I also

show new and useful improvements in assembled or "fixed" ammunition adapting the same to use in connection with and the proper discharge of my improved projectile.

In the accompanying drawings, which are intended to be merely illustrative of the principles of my invention, Figure 1 is a longitudinal section of an assembled ammunition unit intended for submarine shooting and embodying my invention; Fig. 2 is a sectional view along the line II-II in Fig. 1, and Fig. 3 is a similar view to Fig. 1 showing my invention adapted to small arms shooting.

The following is a detailed description of the drawings, reference being first had to Figs. 1 and 2. A is the usual metal shell or casing adapted to fit into the breach of the gun. 1 is a primer set in the head of said casing and communicating with a tube 2 extending axially of the casing A. The inner end of the tube 2 is open and near said inner end the tube is provided with a plurality of ports or openings 3 cut radially in its perimeter. 4 is a loading port in the head of casing A and 5 is a screw plug by means of which said loading port may be tightly sealed. The inner end of the tube 2 fits snugly into the central opening of a metal disk 6 which in turn fits snugly in the bore of the casing A. 7 is a second metal disk adapted to be fitted snugly in the bore of casing A and provided with a central opening in which is fitted snugly the split head of a funnel member 8. About said funnel member I build up a water-proof wadding of the proper diameter to be forced into the bore of the casing A out of semi-circular blanks 9 of suitable material which is subject to compression. The stem of the funnel member 8 is provided with a plurality of radially placed ports 10. The assembled disk 7, wadding 9 and funnel member 8 are then forced into the bore of the casing A snugly against the disk 6, the stem of the member 8 telescoping into the end of the tube 2 and the ports 3 and 10 registering. I next fill in powder or other explosive, a into the open end of the funnel member 8 until the tube 2 is filled. I then fill the open end of the funnel member 8 with suitable wadding or packing 11 and seal the joints between the disk 7 and the member 8 and between said disk and the bore of the casing A with paraffin or other material suitable to keep out the moisture.

B is the projectile of hollow cylindrical form and having the outer or front end of its central bore beveled, as shown to form a sharp annular cleaving and cutting edge. Said projectile is provided with a covering 12 of brass, paper or other relatively soft material which is preferably forwardly tapered, as shown. Said projectile in its covering is forced into the open end of the 10 casing A up against the disk 7. The interior of the casing A is filled up with powder or other explosive, b, through the port 4 and the plug 5 screwed tightly into place. The projectile is now ready to be inserted into 15 the gun or arm. The taper of the covering 12 of the projectile permits the insertion of the latter into the rifled portion of the gun without danger of catching or jamming.

20 When the gun is fired, by means of the primer i, the powder a is first ignited, blowing off the wadding 11 and driving the water from the interior of the projectile and of the gun and also forming a tunnel in 25 front of the gun for the reception of the projectile as it leaves the former. At the same time through the ports 3 and 10 the powder b in the interior of the casing A is ignited propelling the disks 6 and 7, the 30 wadding 9 and the projectile B out of the gun muzzle. The wadding and disks, being relatively light, drop quickly out of the way. The covering 12 of the projectile is preferably made in two sections, one of the two 35 parallel and diametrically opposed lines of separation being indicated at d in dotted line in Fig. 1. Thus the covering readily separates and drops off also as the projectile leaves the gun. If the covering 12 were 40 not readily removable from the projectile, so that it did not drop off therefrom immediately upon the projectile leaving the gun, its presence on the bullet, on striking the water, or in passing through the air in its 45 torn condition, caused by the rifling, would distort the path of the bullet. Thus, the advantage of my readily separable and removable covering 12 is apparent. The projectile enters the tunnel in the water formed 50 by the explosion of the powder a and passes on in its flight. The water encountered by the annular edge of the projectile passes either outside of the projectile or in through its bore with but little displacement and 55 friction, and no tunnel in the water is left behind the projectile as it further advances. Accordingly its flight is true and unimpeded and its trajectory flat. On encountering the object or substance at which it is 60 aimed, the sharp annular edge cuts through and into the latter, leaving a round clean 65 hole of great destructive character.

Referring now to Fig. 3, I have here shown the projectile seated directly in the 55 end of the cartridge A¹ upon a metal disk

13 and the usual wadding 14 which retains the powder b. In this case I do not require the elaborate precautions against the entrance of water nor provisions for expelling the water from the bore of the projectile and the gun barrel, as in submarine shooting. In the case of Fig. 3 I have shown the projectile, marked B¹ as having its outer front wall beveled as well as its inner bore. This is to enable the projectile to extend into the 70 rifled portions of the gun barrel without catching thereon. The covering 12¹ of this projectile is likewise tapered to fit the contour of the projectile.

In the use of my invention in other than 80 submarine shooting, very substantial advantages are obtained. The trajectory of the projectile is flat and its flight true and swift. Where it strikes water, it will enter the same in the true line of its flight, and in 85 striking the object aimed at, a large hole is cut through the same which will not close up in the rear of the projectile and therefore the stopping power of the hit is greatly increased. To compensate for the loss of 90 weight of the projectile, due to its hollow nature, I prolong the same to compensate for the removed material, but the hollow cylindrical form of the projectile holds the same true in its flight and the same will 95 therefore carry much farther and truer than a solid cylinder of the same weight or exterior dimensions.

What I desire to claim is:

1. In ammunition, a projectile of hollow 100 cylindrical form having a constant external diameter and having the forward end of its internal bore beveled outward to meet the external perimeter and form a cutting edge, and a circumferential, soft covering 105 for said projectile, formed in two, readily-separable and removable sections, whereby, as the projectile leaves a gun, the covering separates and drops off.

2. An assembled ammunition unit for 110 submarine use comprising a casing having an inclosed end, a hollow cylindrical projectile inserted in the open end of said casing, an explosive charge in said casing adapted to propel said projectile, and a second explosive charge adapted to expel the water from the bore of said projectile and 115 from the gun.

3. An assembled ammunition unit for 120 submarine use comprising a casing having a closed end, a hollow cylindrical projectile inserted in the open end of said casing, means for expelling the water from the bore of said projectile and from the gun, and means for expelling the projectile from the 125 gun.

4. An assembled ammunition unit for 130 submarine use comprising a casing having a closed end and containing an expelling explosive charge, a hollow cylindrical projec-

tile inserted in said casing, a water tight packing between said projectile and said explosive charge, and a tube in said casing having a packed end adjacent to the bore of said projectile and containing an explosive charge adapted to expel the water from said bore and from the gun.

Signed at Pittsburgh, Pa., this 14th day
of January, 1914.
